UNITED STATES PATENT OFFICE

166,995

BOTTLE OR SIMILAR ARTICLE

Edward Rachins, Brookline, Mass.

Application February 14, 1950, Serial No. 7,926

Term of patent 14 years

(Cl. D58—9)

To all whom it may concern:

Be it known that I, Edward Rachins, a citizen of the United States of America, residing at Brookline, in the county of Norfolk and Commonwealth of Massachusetts, have invented a new, original, and ornamental Design for Bottle or Similar Article, of which the following is a specification, reference being had to the accompanying drawing, forming part thereof.

Fig. 1 is a plan view of a bottle or similar article showing my new design;

Fig. 2 is a front view of the bottle or similar article;

Fig. 3 is a side view looking to the right of Fig. 2; and

Fig. 4 is a rear view of the bottle or similar article.

The opposite side of the bottle or similar article is similar to the side shown in Fig. 3.

I claim:

The ornamental design for a bottle or similar article, substantially as shown and described.

EDWARD RACHINS.
